THERMOSTATIC SWITCH

Lyman H. Walbridge, Ashland, Mass., assignor to
 Fenwal Incorporated, Ashland, Mass., a corpora-
 tion of Massachusetts

Application December 30, 1948, Serial No. 68,126

4 Claims. (Cl. 200—137)

1

This invention relates to thermostatic switches, particularly those of the bowed-strut type as manufactured by Fenwal Incorporated of Ashland, Massachusetts, and as represented for example by the devices of U. S. Patents Nos. 2,090,407, 2,185,433 and 2,257,990. An important object of the invention is to minimize objectionable effects of occasional excessive temperature conditions. This is accomplished under the invention by affording the switches capacity to "overshoot" in the event of abnormal temperature rises. The invention provides an over-travel capacity for the stated type of contact-carrying switch element, applicable in association with various forms of thermo-responsive actuator other than as illustrated in said patents including an external rod and tube type and others. Other objects and advantages will be apparent from the following description in connection with the drawings exemplifying certain embodiments of the invention, and wherein:

Fig. 1 is a longitudinal sectional view of an in-bowed-strut form of the switch, for cool closure and for opening on heating to a set point;

Fig. 2 is a similar longitudinal section of an inverse or outbowed-strut form of the switch, to be open when cool and to close at the selected higher temperature;

Figs. 1A and 2A are cross-sections on the lines 1A—1A and 2A—2A of Figs. 1 and 2 respectively;

Figs. 3, 4 and 5 are partial longitudinal sections showing the Fig. 1 form of the switch in different operative positions: in Fig. 3 the temperature is assumed to be below the set point, the contacts accordingly being closed; in Fig. 4 the assumed temperature is at or normally above the set point and the contacts have opened; while Fig. 5 illustrates the switch as when subject to excessive temperature, abnormally above the critical temperature setting, the contacts remaining open; and

Figs. 6, 7 and 8 illustrate an inverse switch such as that of Fig. 2 under similar temperature conditions as stated for Figs. 3, 4 and 5 respectively.

Referring to the drawings in more particular and first to Figs. 1 and 3 to 5 the switch as a whole comprises a tubular case or shell 10 of metal or other material of appropriate strength and rigidity and having a relatively high coefficient of expansion, that is, distinctly greater than that of the circuit-controlling element to be described. Suitable materials include brass and stainless steel. The circuit-controlling element or switch unit designated generally at 20 is oper-

2

atively disposed within the case 10. It includes oppositely bowed metallic leaf springs 21, 21 composed of a metal having a relatively low thermal expansion coefficient, such as Invar, or a similar nickel-iron alloy, tungsten, etc. In the Fig. 1 embodiment the spring members 21 are bowed inwardly as preferred for the "regular" form of this type of switch, for circuit closure when cool or at relatively low temperatures, breaking on temperature increase to a set point.

The case 10 is closed at its opposite ends by wall means on and between which the circuit controlling element 20 is mounted. At the outer or supporting and adjusting end the case 10 has fixed to it a head or cap 11 with an opening 12 for the insulated electric conductors 13 sealed therein as at 14. The head 11 may be variously constructed and arranged, according to the manner of mounting of the switch, convenience in the location of the conductor entrance, and other factors dependent on particular use requirements, the mounting flange 15 and lateral conductor passage as herein shown being merely illustrative.

The opposite or inner end of the switch case is closed by a rigid wall, herein a plug or disk 16 having threaded or other firm seating engagement with the case 10, the terminal edge of which may be inturned. This end wall or disk 16 carries centrally of the inner portion a rigid post or abutment 17 formed for thrust engagement with the adjacent end of the switch unit 20 in spaced relation to the case end wall 16.

Each spring member 21 of the switch unit 20 has an electric contact, button or point 22 fixed at the central portion as by means of a metal clip 23 surrounding the respective spring and insulated from it by a nonconductive wrap of mica, synthetic sheet material, fibre glass or the like 24. The terminals of the insulated conductors 13 are soldered or otherwise electrically connected to the respective contact clips 23.

The circuit-controlling switch unit 20 has at each end a supporting head 25 and 35. The head 25 toward the mounting end of the switch comprises a tubular body or sleeve 26 with a medial flange 27 which is recessed at opposite sides to receive the spring members 21, 21 laterally. The ends of the latter are inturned and apertured to fit the sleeve, so as to be clamped between the medial flange 27 and a washer-like disk 28 held on the sleeve as by an overset shoulder or end flange 26a thereon.

The described head 25 is installed on and made rigid with the inner end of an elongated anchor

stud 29. This stud has an extensive threaded portion received in the like-threaded axial bore of an adjusting sleeve 30 for regulating the temperature set-point for the switch. This adjusting sleeve 30 in turn has external threaded engagement in a through opening in the end wall of the switch head 11. The insulated conductors 13 may be given one or more turns within the case, herein around a protective tubular positioner 31 extending inwardly from the switch head 11, surrounding and spaced from the anchor stud 29 and the adjustable setting sleeve 30.

At the opposite or inner end of the circuit-controlling element 20 the supporting head 35 comprises a body 36 having medial flange 37 and an outer shoulder or end flange 38. The adjacent inturned and apertured or recessed ends of the contact-carrying springs 21 are at this end of the unit received and held between the medial flange 37 of the head 35 and a washer or disk 39 abutting the end flange 38.

The outer end portion of this supporting head 35 of the switch unit is formed with a central cavity or bore 40 adapted to receive loosely the inner portion of the post or abutment 17 previously mentioned. The free end of the post 17 and the end wall of the bore 40 of the head 35 preferably are mutually shaped in a concavo-convex relation substantially as shown to provide for self-centering and self-aligning thrust bearing engagement with each other. The depth of the bore 40 and length of the post 17 are proportioned to afford capacity for relative bodily movement axially between them over an appreciable distance while retaining relative axial guided alignment. The head 35 and post 17 thus constitute an automatically aligning bearing and abutment couple, with capacity for relative separation in the direction axial of the case 10.

The head 35 and the switch unit 20 as a whole when assembled in the case 10 are held against relative turning, without interference with the capacity for relative longitudinal expansion and contraction. Suitable means for the purpose may be for example as in Patent 2,257,990 previously mentioned, including one or more internal ribs 10a on the case 10 slidably received by corresponding notches 21a in the main flange 27 of the head 25; see particularly Fig. 1a, also Fig. 2a with reference to the embodiment of Figs. 2 and 6 to 8.

Referring now to the outer or mounting end of the switch, at the right in the views, the described stud 29 and sleeve 30 in cooperation with the case head 11 and associated parts to be described provide for adjusting the switch to and securing it at the selected temperature setting. Similarly as in said Patent 2,257,990 the threading of the stud 29 and the internal threading of the sleeve 30 are of different pitch than the external threading of the sleeve and of the case head 11 which receives the latter. Turning of the adjusting sleeve 30 in one or the opposite direction consequently bodily shifts the stud 29 lengthwise in or out. This accordingly increases or decreases the extent of longitudinal expansion of the case 10 requisite for actuation of the relatively non-expanding leaf springs 21.

Herein novel provision desirably is included for insuring retention of the adjustment at the selected set point, against unintended alteration. Accordingly the adjusting element or sleeve 30 has threaded on it a transversely slotted collar 50 having ears 52, 53 in alignment on the respective divided portions. A lock screw 54 is threaded

through aligned threaded apertures in the ears 52, 53. A non-threaded extension 55 of the lock screw 54 projects into a recess 56 for the purpose in the case head 11. Turning of the screw 54 in one direction biases the ears 52, 53 toward each other, causing the collar 50 to grip and hold the sleeve 30 in any set position and against unintended relative turning of the latter. Unison turning of the sleeve 30 and the collar 50 is positively prevented by the extension 55 of the lock screw 54 into the case head 11. When it is desired to change the setting preliminary release of the lock screw 54 permits the sleeve 30 to be turned in the appropriate direction to increase or to reduce the compression on the switch unit 20.

The switch embodiment of Fig. 1 and Figs. 3 to 5 maintains circuit closure when cool or comparatively so. Thus it is particularly adapted for applications where a circuit is to be broken in response to temperature rise, the switch setting being adjusted for opening of the switch points 22 upon arrival of the particular critical temperature concerned. In the cool status, at temperatures below the set point, the switch unit 20 is in some degree of longitudinal compression, being installed and adjusted to a closing compression at average expected ambient temperatures, for example, room temperature. The described adjustment to the desired set point for opening may be made initially or subsequently at the place of use. This is accomplished by releasing the lock screw 54 and turning the sleeve 30 in the appropriate direction to increase the compression upon the switch unit, as calibrated for the particular switch.

One turn of the adjusting sleeve 30 may be equivalent, merely by way of illustration, to say a 70° F. shift of the set point. Merely to cite one specific example, assuming a room or normal ambient temperature of say 75° F. and a desired opening set point of 285° F. the setting is made such that a 210° rise above 75° F. with the attendant relative expansion of the case 10 will result in switch opening. In other words, the adjusting sleeve 30 is turned in the appropriate direction and to the extent, e. g. three turns at the 70° per turn calibration of the above illustration, to place the switch unit 20 under such longitudinal compression as will be relieved to a switch-opening condition by that degree of differential expansion of the case 10 and the switch unit 20 corresponding to a 210° F. temperature rise. It will be understood that within the total available range of the particular switch, opening set points for relatively high temperatures require a greater longitudinal expansion of the case than those for lower temperatures.

Referring now more particularly to the somewhat diagrammatic Figs. 3 to 5, corresponding to Fig. 1, assume now that the switch has been adjusted to the desired set point for opening, such as at 285° F. of the previous example, or it may be 300°, 350°, 400° or other selected point within the total operative range. Fig. 3 then represents the parts as in the normal or cool status. The switch unit 20 is under appropriate longitudinal compression for the switch points 22 to be closed as there shown. At the right-hand end of the unit 20 the compressive force is applied by the case head 11, the adjusting screw 30 and the anchor stud 29 to the switch-unit head 25 rigid with the latter. Opposing these, at the other end of the switch, are case end wall 16 and the abutment post 17 in direct thrust-bearing engagement with the adjacent

switch-unit head 35. In this embodiment the inherent tendency of the inbowed switch leaves 21, 21 is to straighten, in the opening direction. They may be assembled under some initial compression or otherwise as preferred. The compressive force as above referred to in connection with Fig. 3 opposes the straightening effort and holds the points 22 closed in the cool status.

Fig. 4 represents the same switch unit upon arrival of that temperature to which the set point is adjusted. The switch case 10 has relatively expanded and relieved compression on the unit 20 sufficiently to permit the two inbowed members to straighten enough to separate the switch points 22, 22. The switch circuit accordingly is opened.

Still referring to Fig. 4, it is here assumed that the effective temperature has not excessively or abnormally exceeded the set point. The compression of the unit 20 has been characteristically relieved, adequately for the opening action of the switch points. But the compressive condition as between the opposite ends of the switch is still such that the abutment post 17 and the thrust bearing 36 of the switch-unit head 35 remain in direct contact or substantially so. This condition of longitudinal thrust engagement as between the abutment post 17 and the thrust bearing 36 of the switch-unit head 35 may prevail through any ordinarily expected rise in temperature above the set point, depending on the degree of compression under which the switch is initially assembled.

However, operating conditions not infrequently are encountered wherein the switch may be subjected to extreme temperature rises, of an excessive and abnormal degree. Such emergency condition might be occasioned by the failure of a cooling system in connection with some industrial process, or by the failure of lubrication as for example in the case of a "hot-box" at a railway car journal where the temperature may continue to rise greatly above the set point at which the switch opened, or by fire or other emergencies. Under any such emergency excessive temperature conditions, permanent distortion, rupture or other damage of the switch parts has heretofore occurred. This applies not only to devices of this type in which both ends of the switch unit are rigidly connected to the case, as for example in Patent 2,090,407, but also those in which any capacity for relative axial movement, other than differential expansion, has been available only in the axial direction inwardly as to the case and outwardly as to the switch unit, as for example in Patent 2,257,990, wherein substantial undershooting of the temperature is accommodated.

Again referring to Fig. 4, the switch-unit head 25 at the right is rigidly connected to the case through the post 29. If now the other end or head 35 also were rigidly associated with the post 17 or other adjacent part of the case 10, or were such as to permit only in-movement of the case end member as in Patent 2,257,990, then continued expansion of the case 10 in the presence of some excessive temperature condition would tend to subject the switch-unit 20 to damaging tension. This is likely to cause breakage at the end connections, or to deform the switch leaves, and to disturb the electrical connections and particularly the adjustment of the set point. Hence on restoration of temperature conditions to within the normal operating range the switch would function unreliably or is inoperative.

In accordance with the present invention the construction, arrangement and interconnection for the switch unit 20 and casing 10 as herein disclosed and already herein described with reference to the drawings are made such that excessive temperature rise to the abnormal extent concerned, herein termed temperature overshooting, can occur not only without damaging effect to the switch, but also without disturbing the selected temperature setting. The switch accordingly is afforded the capacity to withstand such overshooting and subsequently to resume normal functioning automatically upon return of temperatures within the ordinary operating range, without necessity for replacement of parts or readjustment to the given set point.

Turning now to Fig. 5 and noting particularly the left end portion, the parts are illustrated in an overshot or emergency excess temperature condition. The case 10 as shown has expanded to such abnormal extent as to carry the end wall 16 and abutment post 17 outwardly toward the left completely out of end-thrusting contact with the switch-unit head 25 and the thrust bearing 36 thereof, to the extent as represented by the spacing 40 indicated on Fig. 5. There is no positive connection between the head 35 and the post 17 or other adjacent case part to inhibit the separating action illustrated. The resultant capacity for free bodily outward movement of the abutment post 17 accordingly leaves the switch unit 20 in a condition of complete freedom from the otherwise resultant excessive tensioning and distortion. Thus the severe stresses and strains characteristic of overshooting are relieved from the switch unit, under the present invention. Further, by reason of the cooperative guiding, aligning and self-centering relation as between the abutment post 17 and the thrust bearing 36 of the switch-unit head 35 subsequent decrease of the temperature to the normal range automatically restores the parts for resumed normal operation and accurately subject to the same opening set-point as previously. It will be understood that in the somewhat diagrammatic views the spacing relations as between the switch points 22 and also as between the abutment 17 and switch-unit head 35 may be regarded as somewhat exaggerated, for clearness.

In Figs. 2 and 6 to 8 the invention is further illustrated as embodied in a thermostat having a switch unit 200 of the inverse type. There the switch struts or leaves 210 are outbowed. The switch points 220 accordingly are open in the cool condition and close to make circuit in response to temperature rise. The case 10, cap 11 and parts associated with the latter, including the anchor stud 29 and setting sleeve 30 may in general be as in the previous figures.

At the right or supporting end the outbowed switch springs 210 are formed with semi-tubular extensions 211, similarly as in Patent 2,185,433. These receive the inner end of the stud 29 and are themselves entered into a head-piece 250 having a flange 251. The stud 29, spring ends 211 and the head-piece 250 are rigidly secured together as by spot welding or otherwise. As indicated in Fig. 2A, one or more internal projections 10a on the wall of the case, similarly as in the previous figures, engage the flange 251 to prevent tortional rotative movement of the switch unit 200 relative to the case 10. The contact points 220, the attaching clips 230 therefor

and the insulation 240 for the respective switch leaves 210 may be as previously described.

At the opposite or inner end, toward the left in the views, the switch unit 200 has separable abutive engagement with the case 10 through the end wall 16 and the post or abutment 17 thereon. In this instance the separable connection affording the overshoot capacity comprises a cup-like thrust bearing or head 350 including a recessed body 360 having at its inner end a central boss 361 slotted to receive the flatwise juxtaposed ends of the outbowed springs 210. The spring ends are welded or otherwise rigidly secured to the bearing head member 350. The central longitudinal bore 362 opening from the outer end face of the body 361 is disposed in axial line with the attached springs 210. It is adapted to receive loosely the abutment post 17. The inner end wall of the bore 362 and the free end of the post 17 again as in the previous embodiment have a concavo-convex relation for mutual self-centering and self-aligning abutive interengagement.

In operation the thermostatic switch of Figs. 2 and 6 to 8 functions in a reverse manner to that of Figs. 1 and 3 to 5, as regards circuit closure. Due to the inverse or outbowed relation of the contact-carrying spring pair 210, straightening tension thereon tends to close the points 220. In the normal or "cool" status the switch is open, as in Fig. 2 and in Fig. 6; compare the latter with Fig. 3 of the earlier views. Thus the Fig. 2 device is especially adapted for uses in which a circuit is to be made or closed in response to temperature increase, examples of such applications being in the fields of refrigeration and air-conditioning.

Fig. 7, comparing with Fig. 4, illustrates the ordinary functioning of the switch unit 200 on arrival of temperature equivalent to the selected set point or but normally above it. The switch points 220 come together and establish the circuit. The thrust couple comprising the abutment post 17 and the switch-unit head 350 remain in thrusting contact or substantially so, in the absence of abnormally excessive temperature rise.

But in the event of excessive temperature conditions such emergency is taken care of with minimum danger of distortion of the parts or disturbance of the selected temperature set-point. By reason of the guided self-aligning and self-centering bodily separable connections as between one end of the switch unit 200 and the case 10, the device automatically accommodates itself to such overshooting of temperature at the switch location. The resultant "overshot" condition of the parts is represented in Fig. 8 where the attendant spaced separation of the post 17 and switch unit head 350 is indicated at 400. There it will be noted that the circuit remains closed, the reverse condition from that in the overshoot status of the previous embodiment, Fig. 5.

Thermostatic switches of the invention as herein disclosed, whether of the "regular" type of Fig. 1 primarily designed for contact breaking upon pre-set temperature increase or of the inverse type of Fig. 2 for contact making in like event, may have a normal operating range of wide extent, as for example from -50° F. up to 400° F. or thereabouts; that is, the set-point for actuation may be at any temperature level selected within such range. Yet the devices of the present invention are capable of overshooting

so as to withstand abnormal excess emergency temperatures as high as 1000° to 2000° F. or more, automatically resuming the intended circuit control upon return to normal operating temperatures, the set-point adjustment and the intended operation being in most instances unaffected by the precedent overshooting.

It has been pointed out earlier herein that the bowed or spring strut element or switch unit may be installed under longitudinal compression or otherwise and it is here noted that the installation may be such as to omit compression or even to place the strut end supports initially under longitudinal tension. Thus it is apparent that as to either of the embodiments, whether the inbowed form of Figs. 1 and 3 to 5 wherein the spring bias of the struts is normally toward a separation of the contacts or the out-bowed form of Figs. 2 and 6 to 8 wherein the natural spring bias is toward closing of the contacts, the circuit-conditioning relation of the contacts may be for any given initial or "normal" temperature setting arranged as circuit-making or as circuit-breaking accordingly as the switch unit or element is initially installed under longitudinal compression or under longitudinal tension. Thus as to either the "regular" type of Figs. 1 and 3 to 5 or the "inverse" type of Figs. 2 and 6 to 8, the directional sense of the circuit-conditioning relation of the contacts may also be determined in accordance with the presence or absence of initial longitudinal compression or the presence or absence of initial longitudinal tension. Hence irrespective of the direction of spring bias or bowing of the struts the switch of the invention may be characterized as of the compression or of the tension type. From this it will be further apparent that in certain embodiments the materials or metals of the shell and of the contact element or switch unit may be selected to have substantially the same and preferably low properties of and capacity for thermal elongation and contraction, the shift in the circuit-conditioning relation of the contacts then being determined by variation in the effective longitudinal force, by way of augmenting or relieving the compression or the tension as the case may be. The provision for over-travel herein disclosed as between the contact element or switch unit on the one hand and the shell or the positioning connection between it and the adjacent end of the element or unit on the other hand is equally applicable in any instance, whether actuation results from differential expansion and contraction as between the element and the shell or from variation of the compression or the tension effective upon the element or by a combination of thermal and compression-tension variations.

It will be evident that the novel means herein disclosed accommodating the thermostatic switch to overshooting may be incorporated at either end of the switch units 20 and 230, the same applying also to the means for adjusting the set point, and that said means need not necessarily be at the opposite ends of the unit as shown herein by way of example and as preferred for ease in manufacture and assembly.

My invention is not limited to the particular embodiments thereof illustrated and described herein, and I set forth its scope in my following claims.

I claim:

1. A thermostatic switch comprising an elongated case having a relatively high expansion coefficient, a switch unit therein including a lon-

5 longitudinal pair of oppositely bowed spring strips with a relatively low expansion coefficient, strip-connecting heads at the respective ends of the switch unit, a longitudinally adjustable stud extending into the case at one end thereof, and supportive connections between the stud and the adjacent switch-unit head and between the other case end and the switch-unit head adjacent thereto, one of said connections comprising separable interfitting elongated post and cup abutment and bearing formations with terminal concavo-convex relative shaping for self-centering axial abutive thrusting engagement, release and reengagement providing for extension of the case independently of the switch-unit under temperature overshoot.

2. A thermostatic switch comprising an elongated case having a relatively high expansion coefficient, a switch unit therein including a longitudinal pair of oppositely bowed spring strips with a relatively low expansion coefficient, strip-connecting heads at the respective ends of the switch unit, anchor means rigidly connecting one switch-unit head and the adjacent end of the case, an abutment post fixed on and projecting inwardly at the other case end, and a post-receiving cup-like bearing formation on the corresponding switch-unit head, said post and bearing formation defining a self-aligning axially separable thrust couple of extensively overlapping axial reach and adapted automatically to relieve the switch from temperature overshoot effects.

3. A thermostatic switch comprising a case, a pair of oppositely bowed contact-carrying spring strips longitudinally disposed in the case, strip connecting heads at each end of the pair, positioning connection between the heads and the case portion respectively opposite each of them, said connections for one head including a stud having an adjusting sleeve threaded thereon and extending out through the case in threaded relation thereto whereby turning of the sleeve axially shifts the stud for selecting the set-point for the

5 switch, and locking means for the adjusting sleeve including a transversely divided lock collar externally received on it, axially aligned clamp-screw receiving formations on the respective divided portions of the collar, a clamp screw extending through said formations and a recess in the switch case to receive the inward extending end of the screw.

10 4. A thermostatic switch comprising an elongated case having a relatively high expansion coefficient, a switch unit therein including a longitudinal pair of oppositely bowed spring strips with a relatively low expansion coefficient, strip-connecting heads at the respective ends of the switch unit, a longitudinally adjustable stud extending into the case at one end thereof, supportive connections between the stud and the adjacent switch-unit head and between the other case end and the switch-unit head adjacent thereto, one of said connections comprising separable abutment and bearing formations providing for extension of the case independently of the switch-unit under temperature overshoot, an adjusting sleeve threaded on the stud and itself threaded through the case, a lock collar threaded externally onto the adjusting sleeve, and releasable means for gripping the collar and sleeve against relative turning and for positively engaging the case to prevent unison turning of the collar and sleeve relative thereto.
